UNITED STATES PATENT OFFICE.

FREDRIK WILLE, OF WARREN, OHIO.

PLANT FOR THE MANUFACTURE OF METAL SHEETS OR STRIPS.

Application filed August 27, 1923. Serial No. 659,460.

The invention described herein relates to improvements in plants for manufacture of sheets or strips from ingots, blocks, or slabs, as hereinafter more fully described and 5 claimed.

In the accompanying drawings forming a part of this specification, Fig. 1 is a diagrammatic view illustrating the manner of combining the several reducing feeding, annealing and shearing elements embodied in the invention claimed herein; Fig. 2 is a plan view showing portions of the cooling bed and the feed tables arranged on opposite sides thereof; Fig. 3 is a sectional elevation on a 10 plane indicated by the line III—III, Fig. 1; and Fig. 4 is a sectional detail view of means for moving the sheets or strips across the cooling bed.

In the practice of the invention a feed 20 table 1 is arranged along in front of and in such proximity to one or more heating furnaces 2 that articles to be reduced can be readily withdrawn from the furnace and placed on the feed table which extends to the 25 universal mill indicated at 3. As reduction in this mill is effected by back and forth passes, the rollers of the section of the feed table adjacent to the universal mill are reversible and operated to feed the article to 30 the mill on the forward pass and receive it from the mill on the back pass. In the rear of the mill is arranged a second feed table 4 having reversible rollers. After reduction in the universal mill, the article may be shifted 35 to a cooling bed or fed by the table 4 to a continuous mill consisting of a plurality of two-high stands of rolls 5, the rolls of said stands being driven by any suitable means known in the art in such manner that 40 the rolls of each succeeding stand shall have a higher peripheral speed than those of the preceding stand proportional to the reduction effected in such preceding stand. It is preferred that the last stand of the continuous 45 mill should be driven independently of the other stands which, as shown in Fig. 1, may be driven from a common motor. A feed table 6 is arranged at the delivery end of the continuous mill for delivering the 50 article to the cutting mechanism 7.

As is well known to those skilled in the art, the slab can be so rolled in a universal mill as to produce any desired width of sheet or strip, dependent, of course, on the dimensions 55 of the mill, and also any desired gauge e. g. one eighth of an inch or thicker, but it has

been found that to reduce a slab to a width of thirty inches or less in a universal mill requires the employment of very long feed tables having reversing rollers to effect the 60 back and forth passes. Hence in the universal mill the article is reduced by the vertical rolls to or approximately to the desired width but only a partial reduction to gauge or in thickness is effected by the universal 65 mill, final reduction to gauge being effected by the continuous mill. As for example, the operator knowing the most efficient rate of reduction in thickness effected in the several stands of the continuous mill, will reduce in the universal mill to a gauge or 70 thickness, that by the action of the two-high mills will reduce the article to the finished gauge.

When sheets of a greater width than thirty 75 inches are desired, the slabs are reduced to the desired gauge or thickness and the sheets are then transferred by "kick-offs" indicated at 8 to the cooling table 9 extending at right angles to the feed table. Any suitable means known in the art may be employed for shifting the sheets across the cooling bed onto the feed tables 10 having reversibly driven rollers. As shown in Figs. 3 80 and 4, such shifting means may consist of 85 bars 11 provided with pivotally mounted dogs 12 adapted to be tipped and pass under the sheet when the bars are moved to the left in Fig. 3, but will engage the rear edge of the sheet when the bars are moved to the 90 right. A convenient means for reciprocating the bars consists of a lever 13 having their free ends connected to the bars and connected by links 14 to crank arms 15 on a driven shaft 16.

As in most cases it is desirable to anneal 95 the sheets, a continuous annealing furnace of any suitable construction 17 is arranged at one end of the feed table 10, and by preference a feed table 18 is arranged at the discharge end of the furnace to carry the sheet to the side shears 19 and to and through the shears 20, arranged transversely of the feed table 18. By means of the side shears 19 the sheet is cut to the desired width and by the shears 20 the end of the sheet may be trimmed and if required cut any desired length.

In lieu of cooling the strip as it comes 110 from the continuous mill, it may be desired to trim the edges and cut it into sections or to anneal it and then trim it and cut it. To

this end a table 21 is arranged at right angles to the feed table 6 as shown in Fig. 1 and the strips as they come from the continuous mill are pushed laterally from the feed rollers and onto the table 21 by a "kick-off", and then moved across said table onto a feed table 10 by means similar to that shown in Figs. 3 and 4 and hereinbefore described. The feed table 10, preferably extends across the ends of the tables 9 and 21 and at the end opposite that at which the annealing furnace is located, are arranged side and squaring shears 22 and 23.

As hereinbefore stated, the feed rollers of the table 10 are reversible, rendering it possible to feed the sheet either through the annealing furnace or if annealing is not desired, the sheet may be fed in the opposite direction and be trimmed and cut by the shears 22 and 23. And further, the strip formed by the continuous mill can be fed either directly to the shears 22 and 23 or be moved in the opposite direction through the annealing furnace and then trimmed and cut.

I claim herein as my invention:

1. In a rolling mill plant, the combination of furnace, a universal mill, reversible feed tables arranged on opposite sides of the universal mill, a feed table arranged approximately parallel with the feed table on the delivery side of the universal mill, means for transferring articles from the latter onto the second feed table, and an annealing furnace adapted to receive an article from the second feed table.

2. In a rolling mill plant the combination of a furnace, a universal mill, reversible feed tables arranged on opposite sides of the universal mill, a continuous mill consisting of a plurality of two-high stands of rolls adapted to receive articles from the feed table on the delivery side of the universal mill, a feed table at the delivery end of the continuous mill, a second feed table parallel with the receiving table of the continuous mill, means for shifting an article laterally from such receiving table to the second feed table and trimming and squaring shear mechanisms arranged in operative relation to the second feed table.

3. In a plant for the manufacture of metal sheets, the combination of a furnace, a universal mill, reversible feed tables arranged on opposite sides of the universal mill, a continuous mill consisting of a plurality of two-high stands of rolls, a feed table on the delivery side of the continuous mill, a reversible feed table arranged approximately parallel with the feed tables on the delivery sides of the universal and continuous mill, means for shifting articles laterally from said mill tables to the second feed table, a continuous annealing furnace at one end of the second feed table and trimming and squaring shears arranged in operative position adjacent to the other end of said feed table.

In testimony whereof, I have hereunto set my hand.

FREDRIK WILLE.
